UNITED STATES PATENT OFFICE.

THOMAS G. HALL, OF BROOKLYN, ASSIGNOR, BY MESNE ASSIGNMENTS, TO
THE INTERCHANGEABLE TOOL COMPANY, OF NEW YORK, N. Y.

CUTTING-NIPPERS.

SPECIFICATION forming part of Reissued Letters Patent No. 10,028, dated February 7, 1882.

Original No. 209,677, dated November 5, 1878. Application for reissue filed January 16, 1882. Patented in England September 24, 1878, in Germany June 12, 1879, and in France February 20, 1880.

To all whom it may concern:

Be it known that I, THOMAS G. HALL, of the city of Brooklyn, in the county of Kings and State of New York, have invented a new and useful Improvement in Nippers, of which the following is a specification.

In Letters Patent No. 64,664, granted to me May 14, 1867, a pair of nippers is shown in which the movable cutting-jam is at the end of a lever that is operated upon by a pivoted handle, whereby great power is obtained upon the cutting-edges.

The object of my present invention is to furnish nippers that have great cutting power, and to lessen the expense of their manufacture.

The invention will first be described in connection with the drawings, and then pointed out in the claims.

In the accompanying drawings, Figure 1 is a side view of my improved nippers with one of the side plates removed. Fig. 2 is an edge view of the nipper.

Similar letters of reference indicate corresponding parts.

25 *a b* are the jaws of the nippers, formed with cutting-edges, as usual. The jaws *a b* are each at the outer end of the levers *c d*, respectively.

e is the fulcrum-pin of lever *c*, and *f* is the fulcrum-pin of lever *d*. The jaws are opened 30 by a two-armed spring, *g*, held by a pin, *h*, between the levers.

35 *i k* are the handles, that are hung upon fulcrum-pins *l m*, respectively, so that the handles act as levers. The inner handle, *i*, is formed as a toe, *n*, that acts upon the lever *c*, and the handle *k* is formed with a toe, *o*, that acts upon the lever *d*. The toes *n o* of the handle-levers *i k* work in cavities *n' o'* of the levers *c d*, thus throwing the jaws *a b* each toward the other until the stop-pin *q* is reached. 40 These parts are sustained by the side plates, *p p*. The fulcrums *e f* of the levers *c d* and fulcrums *l m* of the handles *i k* are screw-pins, that are entered through holes in one plate *p* and screw into holes in the plate *p* at the opposite side. The parts are thus securely held together.

q is a pin held by the plates *p* between the outer ends of the levers *c d* in such a position that the jaws or levers will bear against the 50 said pin *q* just before the cutting-edges come into contact, to prevent injury to the edges by contact or overlapping.

The nippers are operated by pressing the handles *i k* toward each other. Each jaw *a b* 55 is acted upon by compound leverage, and the pressure upon any article placed between the cutting-faces is augmented by the dual construction of the parts. The parts of the nippers are compact and strong and not likely to 60 break by any pressure that can be applied by hand. The nippers are easily put together or taken apart for repairs, and the parts are of such shape that the lever-jaws are interchangeable, as are also the handles.

Having thus fully described my invention, I 65 claim as new and desire to secure by Letters Patent—

1. A cutting nipper consisting of the following parts, constructed and combined as described, viz: two jaw-levers, *c d*, upon one end of each of which a jaw and cutting-edge is made, and each of which is suspended upon an independent fulcrum, *e f*, between two side plates, *p p*, two handle-levers, *i k*, each of which is also suspended upon an independent fulcrum between said side plates, and each of which is provided with a short toe, *n o*, set between the long ends of the jaw-levers, but not connected to them, for the purpose of closing the nippers, 80 and a spring, *g*, held between said side plates and set between the jaw-levers, for the purpose of opening the nippers, substantially as shown and described.

2. The combination, with the levers *c d* and 85 plates *p*, of the pin *q*, arranged between said levers and in front of their fulcrums, as and for the purpose specified.

THOMAS G. HALL.
